UNITED STATES PATENT OFFICE.

JOHN E. BUCHER, OF COVENTRY, RHODE ISLAND, ASSIGNOR TO NITROGEN PRODUCTS COMPANY, A CORPORATION OF RHODE ISLAND.

PROCESS OF FIXING NITROGEN.

1,091,425.

Specification of Letters Patent. Patented Mar. 24, 1914.

Application filed October 21, 1912. Serial No. 726,924.

To all whom it may concern:

Be it known that I, JOHN E. BUCHER, a citizen of the United States, residing at Coventry, in the county of Kent and State 5 of Rhode Island, have invented certain new and useful Improvements in Processes of Fixing Nitrogen, of which the following is a full, clear, and exact description.

This invention relates to the fixation of 10 nitrogen and more particularly to an improved process of preparing cyanogen compounds and derivatives therefrom, together with valuable by-products incident to the production of such a compound or compound.

The process in question is essentially synthetic in character in its preferred form, and was suggested by my work on the synthesis of cyanids and on my processes for 20 purifying and preparing metals, in which nitrogen plays an important part. Applications for Letters Patent for these processes have been filed in the United States Patent Office, being there identified as applications Serial Number 676,399, dated February 8, 1912; Serial Number 690,886, dated April 15, 1912; Serial Number 710,758, dated July 22, 1912; and Serial Number 25 711,211, dated July 24, 1912.

One of the equations representing the fundamental ideas of catalysis and reversible reactions upon which these four applications are based is the following:

In the latter application, particular attention is called to the fact that I was able to convert carbonates such as those of sodium into cyanids, and the present application is the one so referred to in my said application, Serial Number 711,211, in this connection.

One of the objects of the present invention is to synthesize cyanids from nitrogen 45 and carbon by the use of compounds such as alkali carbonates, hydroxids, etc., instead of using the corresponding free elements. The following equation may be cited as an example:

The empirical commercial preparation of

cyanogen derivatives from alkali compounds dates back more than two centuries. From about 1828 to 1845, much of the most 55 important scientific work on the preparation of cyanids from atmospheric nitrogen and alkali carbonates was done, and it was during this period that the formation of potassium cyanid in blast-furnaces was affirmatively noted.

As early as 1839, Lewis Thompson claimed to have experimentally determined that a mixture of coke, cinders or coals, potassium carbonate (potash or pearlash) and iron 65 turnings ground into a coarse powder and heated to "full red heat" in an open crucible and in an open fire, produces more cyanid than is obtained when air is not present. His paper, in the English periodical— 70 *The Mechanics Magazine* No. 822, page 92, is primarily of interest as showing the addition of iron which has been used in certain subsequent cases. He further positively states that "the potash is decomposed 75 by the iron, producing potassium, which being volatile, rises and combines with the carbon of the coke and with the nitrogen of the atmosphere, the oxygen of which has been removed by passing through the fire, 80 or by the coke or cinders." He intimates that "when iron is not employed, a much higher temperature is required." He also states that "the carbonaceous matter employed may be worked over again many 85 times, and is even improved by each operation." His statement of the function of the iron, is, I believe, widely at variance with the facts, as evidenced by the disclosures made in this and my above referred 90 to patent applications; and he certainly conveys no hint of the necessity for maintaining the proper surface, contact and other reaction conditions, to which I shall herein-after refer.

That Thompson, if he indeed actually did form any material quantity of cyanid by means of atmospheric nitrogen, had not made such a disclosure as would permit of the process being used by those skilled in 100 the art, is proven by the lapse of time, over seventy-two years, and by the comments on his work by the most noted authorities of his time, namely Berzelius in his *Year-Book*

(German) relating to the progress of chemistry and mineralogy, vol. 21, pp. 80 and 81, published in 1842. After reviewing Thompson's article in *Dingler's Polytechnic Journal*, vol. 73, p. 283, he concludes in substance with the observation:

"The question as to whether coke gives more cyanogen in this operation than corresponds to the nitrogen it contains, yet remains to be decided."

Erdmann and Marchand in the "Journal für Praktische Chemie," vol. 26, p. 413—1842, after reviewing the investigations of Fownes on the formation of cyanid from

15 wood, charcoal or coke heated to a medium red heat with potassium carbonate, refer to Thompson's process substantially as follows:

"This process consists in igniting a mixture of two parts potash, two parts coke or 20 bituminous coal (steinkohlen) and one part iron turnings in an open vessel permitting the access of air. Hereby a greater yield of cyanid was said to be obtained than by the ignition of the potash with animal substance 25 and iron. With one pound of pure potash, 2.8 ounces of pure Prussian blue were obtained.

30 "Berzelius (*Jahresbericht* 21, page 80) comments upon this that it is questionable whether the quantity of cyanogen is larger than could be produced from the quantity of nitrogen in the coke. Before this is shown by experiment, one cannot decide what importance Thompson's process has in its 35 theoretical and practical relations.

40 "The statements of Fownes led us to have the experiments repeated. A mixture of equal parts sugar charcoal and potassium carbonate was exposed to a protracted red heat in a nitrogen current which was prepared from atmospheric air which passed over incandescent copper. Cyanid formation did not take place presumably because the temperature was not high enough.

45 "A second experiment in which the temperature was very much higher, gave with initially abundant evolution of carbon monoxide which contained noticeable quantities of potassium vapor, only a doubtful trace of 50 cyanid formation.

55 "In a third experiment, in which impure potash containing potassium sulfate was used, the presence of potassium sulfocyanid was shown quite plainly. Therefore, it seems as though cyanid formation as Fownes described it, may well take place but not without having certain conditions which have not yet been exactly determined, fulfilled."

60 Bertelsmann in his *Cyanogen Compounds (Cyanverbindungen)*, Berlin, 1906, page 62, states in substance:

"As early as 1839, Lewis Thompson showed that potassium cyanid forms when

air is led over a red glowing mixture of 65 coke, potassium carbonate and iron turnings, however, it was not yet shown that the nitrogen came from the atmosphere and not in some way from the coke."

This writer after referring to the investigations of Thompson, Fownes and Young, Erdmann and Marchand, Langlois, Rieken, Delbrück, and Bunsen and Playfair, makes the following statements:

"Industry very soon began to make use 75 of these investigations and in the forties of the preceding century the first patents for the utilization of atmospheric nitrogen were taken out. Simultaneously, small works were erected to operate the new processes 80 but these had to be closed after a few years. Similar industrial enterprises arose at a later time but all had the same negative result."

85 In 1845, Bunsen and Playfair in a very careful and comprehensive investigation of the action of a blast furnace in England, showed that potassium cyanid is formed in large quantities in the hottest part of the furnace. Furthermore, they claimed to have 90 found that by heating charcoal prepared from sugar with pure potassium carbonate in nitrogen, in a gun barrel, potassium cyanid is obtained. In these experiments, 95 iron was inadvertently present, in one case from the reduction of ores in the blast-furnace and in the other from the probable composition of the gun barrel used in the experiment. The theories which Bunsen and Playfair advanced to account for the phe-

100 nomena were, however, inadequate, and the art does not appear to have been greatly advanced by their efforts. For example, they clearly did not recognize the rôle that the iron played in the experimental part of their work; but apparently considered potassium carbonate, nitrogen and carbon, the only substances which were immediately concerned in the chemical reaction. Indeed, in 105 1845, Bunsen proposed to effectuate their discoveries commercially by constructing a special blast furnace for producing potassium cyanid from potassium carbonate, charcoal, and air; but in the accounts of this attempt, to which I have had access, I have 110 found no reference to the use of iron in connection therewith, and such unsatisfactory results were obtained that the process had to be abandoned. The omission of iron (or its equivalent) in itself, would be sufficient to 115 account for the failure of his process; since without the use of such a material his temperature of operation must have been prohibitively high, especially from a commercial standpoint.

120 The failure of Thompson and others to make the disclosures necessary for the successful use of iron, was one of the factors 125

which led to the practical failure of the direct synthesis of cyanids from atmospheric nitrogen and carbon, not only in the case of carbonates such as potassium carbonate, but even in the case where the free alkali metals themselves were used. This is true in spite of the fact that the following two thirds of a century represents a period of intense activity in the attempt to get a really satisfactory process for this purpose.

Vast sums of money have been spent in attempts to operate some of the processes described in the numerous patents which have been issued. In these patents almost innumerable disclosures and differentiations have been made. In many cases these are contradictory and in some cases manifestly impossible. In some cases iron was used, and in other cases not, with apparently nothing in favor of the cases where iron was used. In fact, the cases which proved to be more nearly successful were those in which the inventors did not add iron.

The confusions and contradictions both in theory and practice no doubt were due at least in part to the use of iron in the form of retorts, tubes, furnaces, etc., in the processes, thus unconsciously having iron present with the reacting substances consciously employed. In some other cases, inventors took no account of the presence of impurities such as ash in coke, coal, charcoal, etc., which under the conditions of the process might produce iron, silicon, calcium, aluminum, and other catalytic agents. In still other cases, not the slightest attention was paid to the formation of these same catalytic agents from the porcelain, fireclay or linings which were in contact with the reacting substances. Certain of these cases which bear more directly on the disclosure set forth herein will be hereinafter considered.

Such lack of definiteness in the experimental conditions could lead only to conflicting theories of the process and ultimately to great confusion in specifications, claims and disclosures, and all sorts of complicated steps were introduced to obviate real or fancied difficulties. Some of these involved processes, as set forth in the printed descriptions of the same, marked distinct retrogressions as compared with the apparently more nearly correct and less involved work of Lewis Thompson, Bunsen and Playfair, and several others in the early history of the cyanid synthesis. Reference may be made in this connection to the German patents to Alder, Nos. 12,351—18,945—24,344 and 32,334. Alder, like Thompson, states that the addition of iron acts very favorably in promoting cyanid synthesis. Alder, however, seems to have been led astray in his work and probably his lack of success was due to his failure to note what the previous

experimenters had also over-looked, *i. e.* the conditions of prime importance to success which I shall hereinafter refer to in detail. As a result, Alder attributed the cyanid formation to the presence of carbon-containing gases such as carbon monoxid and hydrocarbons in the nitrogen.

I have found that quantitative formation of cyanid from, for example, alkaline carbonates takes place readily without the addition of hydrocarbons, carbon monoxid, or the like to the nitrogen. Furthermore, Alder's disclosures concerning temperature conditions are very vague and, in fact, add practically nothing to the state of the art as known at that time.

According to the German chemist, Taüber, in his article on Tests of Sulfurous Organic Substances for Nitrogen, published in the *Reports of the German Chemical Society*, 1899, vol. III, Article 467, Alder's processes were abandoned after being tried for six years, presumably on account of the great technical difficulties which were encountered; and his unsuccessful efforts have made so little impression on the art that the particular processes in question are apparently only slightly referred to in such a recent treatise upon this subject as Robine and Lenglen's—*The Cyanide Industry*, Le Clerc's translation, published in New York in 1906; while in Bertelsmann's work—*The Technology of the Cyanogen Compounds*, published in Munich and Berlin in the same year, some reference is made to Alder's processes, but they are seriously questioned as to their value or utility. Others made use of iron, nickel, cobalt and similar metals in their processes for attempting to produce cyanid, but obtained more or less inconsistent and conflicting results. In fact so little success has heretofore attended processes using iron, etc., as carriers of carbon, that these attempts seem not only to have been abandoned but some have even gone so far as to deny the activity of iron even in case of the complete synthesis from free alkali metal, carbon and nitrogen. Thus Castner, in his United States Patent No. 577,837, dated March 2nd, 1897, and in his British Patent, No. 12,218 of 1894, states that iron is "inert." Very recently Acker, in his United States Patent No. 1,019,002, dated February 27, 1912, disclaims iron as a "reactive" metal in his synthetic process of forming cyanid from alkali metals.

A critical study of such recent works as those of Bertelsmann and Robine and Lenglen, above referred to, as well as the general scientific literature and many of the patents themselves relating to this art, shows that numerous attempts have been made to fix atmospheric nitrogen and that although neither time nor expense was spared, the re-

sults (with the possible exception of costly electric processes) have not been very satisfactory.

Bertelsmann states in substance in his book, above referred to, page 103, lines 19 et seq.:-

"When one views the whole subject, it must be realized that while neither work nor expense has been spared upon the problem of utilizing atmospheric nitrogen, results have been attained which have been of little practical value."

Robine and Lenglen in their work above noted, pp. 321-322, state:

- 15 "The synthetic processes have the great advantage of producing potassium cyanid as a final product. But in most of these processes this advantage is counterbalanced by serious objections; the temperature required 20 for the reaction is often very high, from which it follows that losses by volatilization occur, besides a rapid wear and tear of the apparatus. Moreover, the conversion is very often incomplete, and the reactions do not 25 always take place as simply as the theory would lead one to expect. Notwithstanding the numerous efforts of investigators and manufacturers, very few of these processes have had any really practical application.
- 30 Not one of the synthetic processes using nitrogen and alkali metals has yet given satisfactory results."

Also:

"Only the methods which start with an 35 alkali (sodium), carbon, and ammonia, with intermediary formation of cyanid, seem to have succeeded."

From this it will be seen that the use of atmospheric nitrogen and of the very cheap 40 alkali carbonates for the manufacture of cyanids had been practically abandoned by (and indeed long before) 1906. Since then, to the best of my knowledge, no further efforts have been made to use these inexpensive 45 materials in a synthetic process of the kind in question, with the exception of the herein described process.

The result of the abandonment of the use of atmospheric nitrogen and carbonates, hydrates, or the like, in the practice of the art 50 has led to the use of such expensive materials as metallic sodium and ammonia. The most recent authoritative discussion of the subject with which I am acquainted is 55 found in *Thorpe's Dictionary of Applied Chemistry*, Rev. Ed. vol. II, London and New York, 1912. One paragraph of the abstracts from the article on cyanids by Dr. Thomas Ewan, (Cassel Cyanide Co., Glasgow) found on page 196 of this volume under the caption: Production of Cyanids from Atmospheric Nitrogen, reads as follows:-

"In every process now used for the pro-

duction of cyanids, the nitrogen is derived 65 from coal more or less directly. The production of cyanids from atmospheric nitrogen is a problem on which both money and engineering skill have been lavished without leading to any financially successful solution." 70

Following this is an interesting résumé of various attempts to produce cyanid, some of which met with initial success, but which, from a commercial standpoint, were found unprofitable.

From the foregoing statement of the art, it is evident that a satisfactory commercial method of producing cyanids from atmospheric nitrogen and alkali carbonates, for example, is not only desirable on account of 80 the cyanids themselves, but even more so for the utilization of atmospheric nitrogen. The solution of these problems forms the subject matter of this application for Letters Patent, and as the desirable characteristics and attendant advantages of such a process are numerous some of the more important are given in the following list:

1. The process should use free atmospheric nitrogen; or, better still, air itself. 90
2. It should make use of inexpensive raw materials e. g. sodium carbonate or bicarbonate. 95
3. It should preferably employ the cheapest catalytic agents, e. g. iron. 100
4. The catalytic agent should be efficient, i. e. it should be capable of promoting the reaction with great rapidity even at relatively moderate temperatures.
5. The catalyst should preferably be capable of being used over and over again, without having to be renewed or purified. 105
6. The process should avoid rapid wear and tear of the apparatus.
7. It should allow the use of a cheap heat conducting material, such as iron, for the receptacle used. 110
8. It should preferably be capable of being conducted entirely by heat generation in the apparatus itself, so that the outside of the apparatus could be embedded in non-conducting material to avoid loss by radiation and conduction and to avoid the destructive oxidizing action of the air and furnace gases on the outside. 115
9. It should avoid loss of alkalis by volatilization.
10. It should avoid loss of cyanids by oxidation, or by the decarburizing action of the iron or the like in the charge or in the 120 container.
11. The yield of cyanid should preferably be substantially quantitative,—all of the alkali compound, nitrogen and carbon finally entering into combination. 125
12. These quantitative yields should be obtained easily, and consistently, when the specifications are followed.

13. The process should be simple in character and rapid of execution so as not to require unduly large or expensive plants nor involve excessive expense for labor and maintenance.

14. It should be capable of yielding pure cyanids not contaminated with excess of alkaline substances, sulfids, ferro-cyanids, cyanamids, etc.

15. The product from the furnace should be rich in cyanids.

16. The product should preferably be capable of being lixiviated very readily.

17. After lixiviation, when used, the moist residue of the carbon and iron (assuming iron to be the catalytic agent employed), should be capable of being used over dry or moist, with either dry or moist sodium bicarbonate as it comes from the ammonia-soda process.

18. It should preferably be capable of converting certain of the impure alkali compounds, such as are obtained in various ways in commercial processes, directly and without purification, into pure cyanids.

19. It should preferably also enable us to convert sulfates, such as those of potassium and sodium, into cyanids in one furnace operation by intermediate reduction and transformation into carbonates.

20. It should be possible to recover the cyanid by distillation, sublimation or by draining it from the apparatus during the operation of the process.

21. The resulting product should preferably be in such condition that it can be converted into ammonia directly with steam, without the necessity of lixiviation or separation of cyanid, thus making the iron and alkali carbonate mixture act both catalytically and cyclically; the carbon and the steam to be added under suitable regulation of temperature conditions.

22. It is desirable, in certain cases, to have a simultaneous smelting process for producing the catalyst, *e. g.* iron, during the course of the operation of and by the process itself.

23. Similarly, in certain cases, it will be desirable to operate the nitrogen fixing process as a combined process for purifying iron and making cyanid.

24. For reasons hereinafter more fully set forth, it should be possible, when desired, to use the catalyst in solid form, and to operate the process at only moderately high temperatures, such as lie below the melting points of copper and even of silver.

25. The process, in some of its phases, should be non-electrolytic, since suitable current is not always available.

26. In the last analysis, an efficient process of cyanid formation should enable us, very cheaply, and without drastic temperature requirements, to transform air and water through the instrumentality of carbon (coal,

coke, etc.) into pure ammonia, with such production of by-products as hydrogen, carbon monoxid, formic acid, oxalic acid, etc.

The hereinafter described process in its several aspects is adapted to fulfil or meet each and every one of the recited desiderata and hence broadly aims to economically fix atmospheric nitrogen in a form whereby it may be utilized either with or without subsequent operations, according to the nature of the ultimate product sought; and it is believed that the influences of the present invention will be felt in a number of industries.

In the accompanying drawings, which form a part hereof and in which like reference characters designate like parts throughout the several views, I have exemplified one form of apparatus in which my process may be effectuated. It is to be understood, however, that this apparatus is but one of many adapted to the purpose in question, and that I am not to be limited thereto in any way; nor indeed by the specific steps or operation of my process as herein set forth, since I am aware that various changes and modifications may be made therein without departing from the spirit of my invention. In general I may state, therefore, that my said invention is to be regarded as limited only by the scope of the appended claims.

Description of Apparatus.—Referring to the drawing: Figure 1 is a longitudinal vertical section of a muffle furnace with retorts in position therein, Fig. 2 is an end elevation of said furnace; the blast lamp being omitted for convenience of illustration. Fig. 3 is a fragmentary section of one of the pipes or retorts, the section being taken on line III—III of Fig. 1. Fig. 4 is a similar section of a retort adapted for the use of air in the process.

Brickwork or other suitable material may be employed in the construction of the muffle 1, and one or more iron pipes 2, serving as retorts, may extend directly therethrough. Caps or unions 3, serve to connect the ends of the retorts to the pipes 4—5; those designated 4 being the pipes for supplying nitrogen or air as the case may be. The gases, notably carbon monoxid, evolved during the operation of the process are conveyed away via pipes 5.

A blast lamp 6 or other suitable source of heat may be disposed in the preferably open end of the muffle and this apparatus should, of course, be capable of heating the retorts up to the reaction temperatures employed; which will be hereinafter very fully discussed.

Assuming that the process is to be conducted in such fashion as to permit the use of air, the latter is led in through pipes 4 and preferably first encounters one or more masses 7 of charcoal or other suitable

oxygen consuming material. These masses preferably substantially fill the pipes at the points where they are disposed so that all of the air is obliged to pass therethrough.

- 5 I prefer to interpose wire gauze spacing or supporting screens 8, or the like, between the charcoal and the body of the reaction mixture 9 which is next encountered by the gases flowing through the pipe or retort; 10 since it is desirable to keep the charcoal away from the charge. During the course of the operation, the alkali metal will be evolved in the manner hereinafter described, and if the charcoal is in contact with the 15 active mass or mixture, it may, by capillary action, or from any other cause, remove a portion of such alkali metal from said mass and thereby reduce the yield.

The mixture 9 preferably consists of pul- 20 verulent coke, graphite, charcoal, coal, or the like, very intimately mixed with finely divided iron and sodium carbonate, or other inexpensive source of the metal forming the base of the cyanogen compound sought, or 25 to be incidentally formed during the operation.

- Considerations of importance.*—Before considering the general reactions involved, I desire to state that I cannot too strongly 30 emphasize the importance of considering what would appear, at first thought, to be merely minor considerations, but certain of which considerations are vital to the success of the process, and the overlooking of which 35 has apparently led to the practical failure of the repeated attempts to effectuate the same. Non-observance of these considerations has led experimenters in this art to apparently partly succeed at one time, when by 40 accident the conditions were propitious, and at other times to meet with total failure or with only such success as would not justify continued operation of the process on a commercial scale.
- 45 The present work is based on a very large number of experiments, but I will here refer particularly to three comparative ones. In these experiments, sodium carbonate and graphite were heated, with nitrogen, in one 50 case without the addition of a catalyzer, in another with the addition of finely divided iron; and the two following equations are very important in considering these cases.

In these three experiments, nitrogen, prepared by passing air through a tube containing red hot copper, was passed through a tube containing the reaction mixture.

Experiment 1.—10 grams of finely powdered graphite and 5 grams of sodium carbonate were heated in a current of nitrogen 65 to between 920° and 940° C. for about fifty

minutes, in a copper tube of one half inch diameter. At this temperature, there was a slow but steady evolution of carbon monoxid and some white fumes passed out of the tubes with this gas. These fumes im- 70 parted a steady though not very intense yellow color to the flame.

Experiment 2.—Suspecting that these fumes were due to the formation of the relatively volatile free sodium rather than to the volatility of the carbonate itself, I heated 5 grams of sodium carbonate with 30 grams of finely powdered iron in a similar copper tube and in a current of nitrogen from 920° gradually up to 1,000° C. for fifty 80 minutes. In this test, the issuing gases did not impart the slightest trace of yellow color to the flame at any time, nor could carbon monoxid be detected. This latter experiment with iron and sodium carbonate alone 85 (the graphite being omitted) proves that sodium carbonate is not sensibly decomposed by finely divided iron at 1,000° C. nor is it volatile enough to give a flame test at the end of the tube. 90

Experiment 1 (continued).—Upon cooling, the copper tube containing sodium carbonate and graphite showed a minute quantity of white material which had condensed on the cooler part of the tube; which deposit consisted at least partly of free metallic sodium. These facts show that at about 920° to 940° C., small quantities of sodium and carbon monoxid are formed according to equation 3. When these two components 100 attain a certain small vapor pressure, the reversible reaction comes to equilibrium. They are then swept along with the nitrogen current and in turn another portion of the carbonate decomposes, thus tending to 105 restore the vapor pressures necessary for equilibrium. The contents of the last mentioned tube were treated with water and tested for sodium cyanid by means of the Prussian blue test. Only traces could be 110 detected even after the solution had stood for a day. This experiment shows that graphite, sodium and nitrogen yield practically no cyanid when heated to the moderate temperature of 920°-940° C. in the absence 115 of a catalytic agent. And even here it is possible that the copper in the tube or the impurities (Fe) in the graphite may have exerted some catalytic influence.

Experiment 3.—A mixture of 10 grams of the graphite, 10 grams of finely powdered iron (*Pharmacopœia Germanica* IV), and 5 grams of sodium carbonate were heated in an iron tube through which was passed a current of nitrogen. With the exception of 125 adding iron as a catalyzer and substituting an iron for a copper containing tube, all conditions were kept as nearly as possible like those of the first experiment. At a temperature of 920°-940° C. as measured by the 130

pyrometer, there was, in this latter case, a steady absorption of nitrogen and the escaping gas burned with the characteristic blue flame of carbon monoxid. Nitrogen was still being absorbed at the end of fifty minutes when the heating was discontinued. The escaping gases contained no fumes nor did they show the slightest trace of yellow color when led into the burner flame, at any time during the experiment. This very sharp contrast with the experiment in which no catalyst was used shows that free sodium did not escape with the gases when iron was used. The contents of the tube were then treated with water and the resulting solution was titrated with silver nitrate. It was found that 60% of the sodium carbonate had been converted into cyanid. Under the conditions of this experiment, the velocity of the reaction was increased at least several thousand-fold, even at this relatively low temperature, by the catalytic action of the iron with a consequent transformation of 60% of the carbonate into cyanid in fifty minutes. A far more rapid formation of cyanid may be effected at, for example, higher temperatures, or by properly varying other conditions, as I shall herein-after show. These and the further experimental results below mentioned, enable us to formulate a theory which is in accordance with the facts and is of great service in connection with the process.

By means of Experiment 1, in which iron was omitted, it was proved that reaction 3 takes place at 920° to 940° C. (and to a less extent at even lower temperatures). Now when comparatively small quantities of sodium vapor and carbon monoxid are present at this temperature, they tend to form sodium carbonate and carbon and thus reverse the reaction; establishing a chemical equilibrium.

When no catalyst is present, the sodium does not unite rapidly with the nitrogen and carbon, and consequently is swept away by the current of nitrogen, so that we have very little formation of cyanid. When, however, finely divided iron is added to the mixture of carbon and sodium carbonate, the mixture being heated to the given temperature as per Experiment 3, the iron will become carburized by dissolving some carbon; thus forming a solid solution of carbon in iron.

Theory of operation.—In chemical work, it is often necessary to dissolve solids to make them reactive; and we also know that when substances are dissolved they very frequently become dissociated. These and many similar considerations point to the conclusion that if the very complex and ordinarily comparatively inert carbon can thus be dissolved it will not only acquire mobility but perhaps may also become less complex; thus approaching the nascent con-

dition. Iron is one of the best solvents known for carbon. Hence a solid solution, such as is obtained in the cementation process of manufacturing steel, will form very quickly at the surface of the metal; provided that it is not already there, as in carburized iron. The conditions at this surface should be exceedingly favorable for chemical reactions and the above mentioned results obtained by the use of finely divided iron are in accordance with this view.

Presumably a part at least of the operation takes place as follows: The small quantity of sodium vapor, formed according to equation 3, and the nitrogen come in contact with the reactive surface of the carburized iron where they combine very quickly with the carbon dissolved in the surface of the iron, forming sodium cyanid. The vapor pressure of the gaseous sodium, is thus reduced and consequently another portion of sodium carbonate decomposes to reestablish the equilibrium. This new portion of sodium vapor in turn combines with nitrogen and carbon at the surface of the iron, which has meanwhile become recarburized by taking up carbon from the carbonaceous masses in contact therewith, or from the carbon in solution in the mass of iron. The iron hence acts as a catalyst by undergoing a series of decarburizations and recarburizations; resulting in the efficient and continuous production of reactive carbon for the process. The very quick combination of sodium at this catalytic surface reduces the concentration of the sodium vapor steadily, and thus materially aids in producing a continuous liberation of sodium with the consequent continuous formation of sodium cyanid. This very simple theory, enables us to deal intelligently with the many conditions which influence the process. Evidently the first requisite is to produce as efficient a catalytic or solution surface as practicable and to maintain its efficiency during the process.

Even when the conditions of surface and contact appear to be correct or nearly so, at times a lapse of 10 or 15 minutes may occur before any vigorous reaction takes place. This may be due, in some cases, especially when working at a relatively low temperature, to the time, consumed in carburizing the reactive surfaces of the catalytic material; and probably also to changes in the relative disposition of fluid and solid constituents of the reactive mass by, for example, capillary action. The theory of the operation must therefore be borne in mind while the actual procedure is really a compromise between various factors. At one temperature one factor becomes dominant; at another temperature, sometimes quite close to the first, another factor gains the ascendancy, and so on.

Should my theory be faulty, which however I do not think is the case, it at any rate supplies a working hypothesis which enables us to achieve consistent and successful results.

Sources and condition of catalyzer, etc.—
A fine state of division of the iron exposes a large surface and hence acts favorably. Similarly a fine state of division of the carbon favors the quick carburization of the iron by providing thorough contact at, what I may term, the solution surfaces, or as I prefer to term it in the aggregate—surface. The iron and carbon should be mixed thoroughly for the same reason, except in those cases hereinafter referred to where the carbon is supplied through the agency of a vapor.

It is of importance to consider both the relative and the absolute size of the particles of carbon and iron as well as the extent to which they are in actual contact.

The catalytic agent, *e. g.* iron, if used in solid form should be quite finely powdered or in such other form as to expose, or to render possible the exposure of, a relatively enormous solution surface. Particularly is this the case when the operation is conducted at temperatures materially below the eutectic point of the carbon-containing material.

If the iron be a coarse powder, insufficient surface will usually be provided, under such conditions, to permit of the process being conducted efficiently. If, on the other hand, it is too finely divided, there is some tendency to pack too tightly and thereby prevent diffusion of the gases and vapors involved. On the whole, however, I prefer to divide the iron as finely as possible and to provide for diffusion in some suitable manner such as will be hereinafter indicated.

When the particles of catalytic material are relatively large, the surface is correspondingly small and the area of contact is likely to be too small for quick and efficient renewal of the carbon content in the catalytic surface. Under the indicated conditions, which I have found convenient in effectuating my process, when nitrogen and sodium were heated with iron, better results were, in general, obtained when the iron was relatively fine and the graphite comparatively coarse, than when the relative sizes were reversed, *i. e.* when the iron was coarse and the graphite fine. Thus iron *Ph. G. IV*, which is far finer than 100 mesh, gave very good results when used with graphite which had been passed through a one hundred mesh sieve but which on the whole was not nearly so finely divided as the iron.

An even better result was obtained when said fine iron was used with graphite of 60 to 80 mesh. When, however, the graphite was of 20 mesh used with this very fine iron

the action was considerably slower. This series of tests, show, therefore, a distinct maximum for the graphite of intermediate coarseness; as was to have been expected since when the particles are too fine the mass lacks porosity and the nitrogen and sodium vapor cannot so easily penetrate the interior of the mass whereby to efficiently contact with the reactive surfaces (or as I herein broadly term it, reactive surface). On the other hand, when the graphite particles are too coarse the fine heavy particles of iron will tend to drop through the interstices and thus become segregated. The latter action would, in extreme cases, be equivalent to removing the catalyzer from the field of action. I find that either of these two extremes may substantially result in the failure to produce cyanid. We should, further, not only consider the sizes of the particles, but also their other general physical properties—*i. e.* shape, smoothness or roughness of surface, whether they are compact or spongy, regular or irregular in shape, whether they are adhesive at the temperature of the operation, etc. For example, if the particles are coarse, spherical or globular, non-adhesive and smooth, they favor segregation, while if, on the other hand, they are fine, irregular, rough and preferably slightly sticky or adhesive at the temperature of the operation, they obviously favor the contact and surface conditions when once established.

It is to be understood that while I regard finely divided iron as generally preferable for use in the process, in view of the possibility of increasing the potency of certain other factors hereinafter referred to, I do not wish to be limited to any particular size, condition or source of the catalyzer or indeed of the size, condition or source of carbon for the same, except where, in certain of the appended claims such limitations are specifically introduced. For example, pulverulent iron may be produced directly in the reacting mass itself from iron compounds or ores, such as oxids, carbonates and the like, *e. g.*, haematite, magnetite, siderite and iron scale.

A mixture of finely powdered hematite, carbon and sodium carbonate may be prepared in such proportions as to leave the iron, graphite and sodium carbonate in favorable proportions for cyanid synthesis after the excess of graphite had reduced the hematite to metallic iron with the evolution of carbon monoxid. Under these circumstances the iron becomes reduced very readily (even if the solid carbon particles should not come in thorough contact with the iron ore, reduction would still take place completely because the molten cyanid formed reduces iron oxids with the utmost ease and even carburizes the iron at the same time). Further, if the temperature be sufficiently

high, sodium vapor will be formed, according to equation 3, which, of course, will act as a powerful reducing agent.

Iron scale (presumably Fe_3O_4) reduced very quickly and gave a very satisfactory yield of cyanid; leaving the resulting iron, after lixiviation of the cyanid, in excellent form for subsequent use with the process. Thus use may be made of a waste product (iron scale), or ore with the simultaneous production of cyanid, metallic iron, substantially nitrogen-free carbon monoxid, and with the removal, in part at least, of impurities such as sulfur, alumina, silica and phosphorus from the reacting mass. I consider that this may be of special interest in the iron and steel industry, especially as the process can be carried out in iron apparatus (which is not attacked by basic materials) at relatively low temperatures with basic re-agents which hence tends to remove the two very troublesome elements, sulfur and phosphorus, as well as acid forming elements in general, including silicon. It presumably removes these elements as sulfids, phosphids or phosphates, silicates, aluminates, etc., and probably some nitrid forming elements in the form of nitrids.

The low temperature, with consequent moderate reduction, to say nothing of the strong alkaline nature of the charge, tends to produce a very pure iron and at the same time affords a process for fixing atmospheric nitrogen. Usually the iron thus obtained will be carburized but this may be decarburized very readily, as described in my said pending application, Serial No. 676,399, by means of the cheap sodium produced from cyanid, as described in my said application Serial No. 710,758.

Carbon.—The carbon may be supplied from a variety of suitable sources and in addition to those mentioned, which are solids, carbon supplying vapors may be used. Thus the hydro-carbons, *e. g.* petroleum, are available for use in certain cases. It is highly desirable usually to substantially completely exclude the oxygen of the atmosphere from participation in the reaction resulting in the production of cyanid, since oxygen either converts the cyanid formed to cyanate; or oxidizes the iron and results in the production of ferro-cyanids or the like upon subsequent lixiviation; or even worse, it may destroy the cyanid formed, with reproduction of carbonate.

The carbon has greater freedom of motion than one might at first expect. Its diffusion is not limited to mechanical motion due to the action of gravity, agitation of the mass, melting of solid material with consequent sintering, washing effect on the particles by currents of liquid due to surface tension, change of concentration, capillarity, distillation of liquids, etc. It is

soluble in the iron, or the like, used as a catalyst, and can diffuse either in the form of solid or liquid solution. It may, in effect, be carried as liquid, vapor, or even as solid in the form of sublimate, by compounds such as cyanids, *e. g.* sodium cyanid. If these latter come in contact with iron lacking in carbon, a reverse action may take place (equation 4), thus helping to carbonize the mass of iron. Indeed, this imparts a mobility to the carbon such as would be attained if the carbon could diffuse as a vapor, thus giving to the carbon, such as graphite, coke, charcoal, etc., in the tube, essentially the same kind of freedom that it would have if used in the form of hydrocarbons. I believe that this may be a matter of great importance under some conditions of cyanid synthesis as it does not require differences in temperature for its manifestation, *e. g.*

For example, in the above indicated disposition of masses of material in the retort (the brackets indicating the respective spaced masses and the tube being indicated by dotted lines) we may form sodium cyanid in the usual manner at A. At B we may have decarburized iron. If now any cyanid be carried from A as a liquid, by distillation or by sublimation to B, the reverse equation 4, will take place at B; equation 4 being a reversible equation, the direction of the reaction depending on mass action, etc. The iron takes up the carbon from the cyanid with the liberation of sodium and nitrogen. This is practically equivalent to transferring the highly non-volatile graphite, in which form the carbon may be present in mass A, at temperatures substantially in the vicinity of the eutectic point of iron and carbon, through the instrumentality of the intermediate formation of a volatile cyanid, to the mass B located in another portion of the tube or retort. Of course, the reaction can be completed at A, first; thus getting rid of carbon monoxid separately, or, the two reactions may take place simultaneously. Also carbon monoxid and sodium form according to equation 3, and, if the reaction becomes reversed at the places where the temperature is lower or the concentration of carbon monoxid is greater, a mass of sodium carbonate and carbon will be deposited, in effect, as though the carbon had distilled as free carbon. This deposition of carbon may help at times when the process is not proceeding as rapidly as might be desired.

Alkali metal.—The source of alkali metal

or other base of the cyanogen compound formed, during the course of the process, is preferably some inexpensive compound such as sodium carbonate, sodium bicarbonate, 5 sodium hydrate, or the like, but it is possible to employ initially free alkali metal or its equivalent.

With respect to sodium bicarbonate I particularly desire to call attention to the fact 10 that I have successfully used the moist bicarbonate which comes from the ammonia soda process; and this without previous drying. Indeed, very many impure alkali compounds which may result from various technical processes can be converted into pure 15 cyanogen compounds. For example, mixtures of alkali hydroxids, carbonates, acid carbonates, acetates, oxalates, etc., can be used directly if iron, oxids, or hydroxids, 20 or organic salts of iron, carbon or organic matter in general be present; and no contamination of the alkali cyanids can occur since the substances of the classes mentioned are so transformed in the process that the 25 only negative radical remaining will be cyanogen. If more than one alkali metal be present, however, a mixture of alkali cyanids will result. When the cyanid obtained is to be transformed into ammonia as hereinafter 30 described almost any other impurities may be present without affecting the purity of the product, providing suitable precautions are taken. Alkali sulfates, can also be used with much advantage in my process. Potassium 35 sulfate is obtained extensively from the deposits at Stassfurt, Germany, while sodium sulfate is obtained in large quantity as a by-product from the action of sulfuric acid on sodium compounds, such as chlorid.

I find that in my process sulfates may readily be converted into cyanids by the 45 following procedure: Pulverulent graphite and sulfates *e. g.* Na_2SO_4 or K_2SO_4 may be heated in iron pipes to temperatures suitable for cyanid formation. At this temperature the alkali sulfates are reduced 50 rapidly to sulfid and carbon monoxid (which is substantially pure). Thus:

The sulfid may now be converted into carbonate even without removing it from the apparatus or separating it from the carbon with which it is mixed. This may be done by allowing it to cool to a suitable temperature and then passing a current of moist carbon dioxid through the mass; or the water in suitable proportions may even be added directly to the mass containing the alkali sulfid and carbon before passing the carbon dioxid through the mass. The chemical

action, in the case of sodium sulfid, may be 65 expressed thus:

or

The mixture of sodium carbonate and carbon, thus obtained, is especially adapted for my process since it is only necessary to mix it with finely pulverized iron followed by 75 subsequent heating with nitrogen at a suitable temperature to convert the alkali carbonate into cyanogen compounds per equation 4.

The cyanid thus produced can be utilized 80 directly as cyanid or it may be converted into ammonia by methods hereinafter described without previous removal from the carbonaceous mass.

The iron required for cyanid formation 85 may also be added directly to the mixture of sodium sulfate and carbon, before heating, so that it is possible to charge the tubes with sulfates and proceed to the formation of ammonia and carbonates without removing the 90 charge or adding solid material thereto.

I have shown that the transference of carbon from one separate mass to another in a tube or retort is possible, and will now consider the somewhat similar but not strictly 95 analogous transference of sodium.

In this case a mass C of sodium carbonate and carbon (without iron) is heated in a 105 current of nitrogen to produce sodium and carbon monoxid according to equation 3. If this current of the three gases, nitrogen, carbon monoxid and sodium be then passed through a mixture D of carbon and iron, 110 cyanid forms, according to equation 4, by absorption and combination of nitrogen and sodium at the catalytic surface of the carbon and iron; while the carbon monoxid passes out of the tube. I have frequently used this 115 mixture of carbon and iron with rather ineffective reaction mixtures to absorb the sodium vapor from the escaping gases, thus doing away completely with loss by volatilization, and the danger of explosions from 120 free sodium when the masses were lixiviated. It is obvious too that sodium carbonate, for example, may be distilled over, from a mass of the same into contact with the material presenting the reactive solution surface. I 125 am of the opinion however that the bulk of the sodium supplied by mass C to mass D passes over as free or metallic sodium in va

porous form. At 920° to 940° C. this sodium vapor would be formed quite slowly at C and be carried to D by the nitrogen which at this temperature would usually make up the greater part of the gas. Mass C being porous, as is also, of course, mass D, capillarity probably plays an important part in both cases. An extended film of the liquid source of the alkali metal hence forms on the carbon particles and this I shall, for convenience, term (whether here or, as in other cases on the iron as well) a "reactive film", since it decomposes under the action of a suitable agent *e. g.* heat to liberate the alkali metal. Presumably if the film at C is very extended the sodium vapor quickly saturates the free space in the porous mass C, thus bringing about a condition of equilibrium. The rate of the sodium vapor would then be determined practically by the flow of the nitrogen current through the tube no matter whether the masses in C and D were an inch apart or many feet apart. For example, if the nitrogen were passed through a one half inch iron pipe at a temperature of 920 – 940° C. or even somewhat lower, at the rate of about 100 cc. per second, it would take a very long time to get a substantially quantitative yield of cyanid at D; and this in spite of the fact that cyanid formation, equation 4, takes place practically instantaneously at this very efficient catalytic solution surface at D.

Equation 4 is apparently of the fifth order, when we consider it as taking place from right to left for the conditions at about 900° C., and the velocity of this retarding reaction would hence vary as the fifth power of the vapor pressure of the two gases, providing that it is of this order. Hence if the catalytic or other action were efficient enough to reduce this vapor pressure down to one tenth of its former value, the retarding effect would be decreased a million-fold.

I am aware that reactions of high order are rare (as stated by Nernst on page 560 of his *Theoretical Chemistry*, 4th edition, New York, 1904); but even if the reaction in question were only of the second order the decrease of the retarding effect would yet be a hundred-fold; while in the lowest order, *i. e.* the first, said effect would still be ten-fold. This demonstrates that in any case the reduction effect is large and it may be, indeed probably is, enormous, as I have indicated.

In the experiments above referred to, the rate of diffusion of the sodium vapor was about a million times as great as the velocity of the nitrogen current. Therefore when the components of the reacting mixture are finely powdered, the sodium molecules have such a short distance to travel that the rate

at which the sodium comes in contact with the reactive solution surface is largely determined by the enormous molecular diffusion velocity rather than by that of the relatively slow sodium laden nitrogen current.

Let us now consider the masses C and D to be superimposed. In this case the particles will be very close together, the masses will interpenetrate and cyanid formation will take place far more rapidly than where the effective supply of sodium is wholly dependent on the rate of flow of the nitrogen current rather than upon the velocity of the molecules of the alkali metal. For example, in the already cited Experiment 3, such interpenetration of the masses C and D (*i. e.* such juxtaposition of the particles of iron and carbon, or such close juxtaposition of the reacting film and the reactive solution surface) was produced by thoroughly mixing the charge of iron, carbon and sodium carbonate previous to its introduction into the tube. The result was a yield of over 60% of the theoretically possible quantity of sodium cyanid, in fifty minutes. This experiment shows that the sodium is given off in close juxtaposition with the catalytic solution surface of carbon in iron.

Temperature.—Temperature also must exert an enormous influence when we consider its various effects. It increases the velocities of chemical reactions enormously, and it also increases the rate at which the carbon goes into solution in the iron; as well as the rates of gaseous diffusion and development of vapors. The temperature of the operation further intimately concerns the surface and contact conditions above referred to.

When the finely pulverized iron and carbon mixture is heated to, or nearly to, the eutectic point (about 1150° C. although it may vary somewhat) it becomes sintered and partly welded or even melted to globules. The surface is thus decreased and the mass of the iron becomes comparatively inert; the action nearly ceasing. Still worse it may even drain away from the carbon source, especially if the materials are coarse. When portions of iron under these conditions are used over several times the yields drop from, let us say, 60% to about 40%; 18%; 7%; 3%, or even less than 1%. This probably accounts in large measure for the failure of many of the previous attempts.

The pulverulent iron may, if it has not been sintered into globules or worse, be used repeatedly, without repulverization. Its condition may even be improved by the operation since the treatment purifies the catalytic metal by removing sulfur, oxygen, and other impurities therefrom, as previously noted. I am aware, however, that the carbon solution need not be solid and that

the process may be made operative at temperatures considerably above the eutectic point of, for example, iron and carbon. For this reason I do not wish to be limited to operations conducted at these relatively low temperatures except when in certain of the appended claims limitations are introduced to that effect. I further do not wish to be restricted to any particular lower temperature limit, except where in certain of the appended claims I have specifically referred to a temperature of 700° C. Indeed, I contemplate effecting the process in certain cases at temperatures below even 700° C., since rubidium and caesium carbonates, for example, and especially mixtures of these, or of one or more of these with sodium or potassium carbonate or analogously acting compounds permit of materially lowering the temperature at which the nitrogen fixing reaction takes place (principally, I believe, by increasing the fluid circulation). By incorporating cyanids initially in the reaction mixture, the same end may also be attained in a measure.

Mobility of reaction mass or masses, and constituents thereof.—In view of the foregoing, therefore, it is evident that the general mobility of the reaction mass and its components must be considered. Change of relative position of constituents of the reactive mass or masses may be due to the melting of alkali compounds (or even the catalyst, to wit, iron, itself) with the consequent change in the position of the particles of carbon and iron, to the velocity of the nitrogen current, to the drainage of the molten compounds under the influence of gravity, to volatility, surface tension, capillarity and the like. From these effects, it is evident that the size and shape of the tube or retort, its inclination, the depth of the layer of reacting mixture, stirring of the charge, rotation of the tube or retort (either continuously or at intervals), etc., should also be considered. The nitrogen, of course, depends on the velocity of the gas current and the molecular diffusion rate under the experimental conditions, for its chief source of motion. In a secondary way it might be carried, for example, in the form of liquid cyanid or cyanid vapors and these, by reverse action, might again liberate the nitrogen to some extent.

55 The sodium may move through the mass in the form of molten compounds, or in the form of vapors of such compounds. It will also, after being liberated by the decomposition of the carbonate (or other compound thereof), equation 3, or the decomposition of cyanid, equation 4, have the same freedom of motion and penetration as the nitrogen, i. e. from the velocity of the gas current and the molecular diffusion velocity of the free sodium.

The effect of volatility has already been discussed under the mobility of the sodium and carbon in the reaction mixture. It may also be of great importance otherwise; as can be seen from the law of mass action and phase rule. It also causes circulation of liquids and vapors, washing action upon particles, and changes concentrations and compositions of mixtures. Besides this, it may help to keep temperature conditions uniform because of latent heat of vaporization. The flowing of molten matter, e. g. sodium carbonate, from whatever cause must have much effect as shown by the above considerations. Flowing of liquid may even cause segregation, by washing away particles of carbon or iron, and thus cause loss of efficiency. On the other hand it may be caused to, or may even inadvertently wash the particles into more advantageous positions, thus causing increased efficiency. Also the molten materials may, as conditions determine, either flow away from or else toward the reacting mixture; and this flow of liquid may therefore act either detrimentally or advantageously. For example, I have noticed that when conditions were not quite right, beneficial results were frequently obtained by simply rotating the tube containing the reaction mixture, about 180°. This is presumably due to the flowing of the liquid by gravity and the consequent surface changes.

I regard the effects due to surface tension or to relatively minute differences in surface tension, as well as to that phase of surface tension which is generally termed capillarity, and also the conditions which modify these, as of much importance.

As the composition of the molten alkali mixture is constantly changing during the process, the surface tension is presumably changed likewise, thus, tending to cause motion of the particles in a well known manner. The finely powdered, porous reacting mass affords exceptional opportunities for capillarity to exert its influence. The powdered mass of carbon and iron will take up by capillarity the liquid independently or separately supplied thereto, or will similarly re-take up the liquid which may have drained by gravity to the lower portions thereof after the content of liquid remaining in the drained portions has been in whole or in part removed; the action being not dissimilar to the way in which a lamp wick takes up oil. In this porous mass of carbon and iron the liquid comes in contact with the very large surface of the iron, and incidentally, of course, of the carbon; while nitrogen can also diffuse to this surface very rapidly, which obviously tends under the prescribed conditions to favor the formation of cyanid; the films of liquid more or less rapidly being dissociated to yield the free sodium, which latter may either react where

liberated or elsewhere on the surface. Preferably the thinner the film the more readily can the nitrogen molecules penetrate it to reach the reactive surface of the carbon supplying iron. When this film is too thick the nitrogen cannot well penetrate and the reaction is impeded. Further, the more extensive the film surface, the greater is the liberation of free sodium per unit of time, together of course, with a correspondingly accentuated evaporation of the liquid compound itself, or of its decomposition products.

If too much molten liquid is present, the pores or interstices will, of course, be more or less filled or choked therewith, thus preventing the required contact of the gaseous materials, such as nitrogen and sodium vapor, with the catalytic solution surface. We may regard the nitrogen as burning the carbon and sodium to sodium cyanid, and if there be either insufficient catalytic solution surface or an inadequately reactive or insufficiently extensive film this peculiar combustion is retarded or in extreme cases may be almost wholly prevented.

The above considerations concerning the mobility, especially that due to capillarity, within the reacting mass led me to make a considerable number of experiments of which the following are typical: An efficient mixture of 40% of graphite of 100 mesh, 40% finely powdered iron (*Ph. G. IV*), and 20% of freshly ignited sodium carbonate was prepared. A flat bottom iron retort 70 mm. by 10 mm. was attached to a long piece of wire so that it could be inserted into a long pipe which was heated to the desired temperature and through which a current of nitrogen was passing.

Experiment 4.—One half a gram of the above reaction mixture containing carbon, iron, and sodium carbonate was tamped into the retort in a uniform layer. The retort was now pushed into the tube which was heated to 1070° C. Not more than a minute was allowed for it to come to the reaction temperature, and it was then allowed to remain for five minutes more in the heated nitrogen. It was then withdrawn to the cooler part of the tube and allowed to cool in the current of nitrogen. Upon lixiviation, so little cyanid was found that it could not be titrated accurately with silver nitrate solution. This experiment was repeated with the exception that the tube was heated to 1000° C.—the result being the same.

Experiment 5.—The retort was again charged with one-half gram of the aforesaid mixture of sodium carbonate, iron and graphite, and six-tenths of a gram (an equal volume, therefore an equal depth of layer) of a mixture of equal parts of the 100 mesh graphite and the iron (*Ph. G. IV*) was

tamped on the surface of the reactive mixture containing the sodium carbonate. This was pushed into the tube containing nitrogen heated to 990° C. As before five minutes was given for the reaction. The yield of sodium cyanid was 25% of that theoretically possible.

Experiment 6.—The operation was now repeated substantially as per Experiment 4, at 990° C. but without tamping the material. Here the quantity of cyanid formed was too small to be titrated with silver nitrate solution.

Experiment 7.—This experiment was exactly like Experiment 5 with the exception that twice as much (one and two-tenths grams) of the above carbon-iron tamping mixture was used, *i. e.*, the layer of tamping material was twice as deep as that used in Experiment 5. In this case, I found that about 50% of the sodium carbonate had been converted into sodium cyanid in five minutes at 990° C.

Experiment 8.—This experiment was like Experiment 7 with the exception that the one and two-tenths grams tamping mixture were placed in the bottom of the retort and the five tenths gram reaction mixture formed the upper layer. The result was substantially the same as that of Experiment 7, *i. e.*, fully 50% of the sodium carbonate was converted into sodium cyanid in five minutes at 990° C. (At another time the same yielded fully 40% in two minutes.)

Experiment 9.—In this case the quantities of material used were exactly those in the preceding Experiment 8, but they were thoroughly mixed instead of being used in layers. In this particular experiment the yield of cyanid was about 40% of the theory, in five minutes at 990° C.

Experiment 10.—This experiment was practically a repetition of that described under Experiment 6, and is cited merely as an exception, since in this case, a small yield of cyanid, to wit, 15% was obtained, which demonstrates that even under what appear to be identical conditions, some variations in yield may occur. In the case in point, the cyanid formation may have been due to some condition such as lack of uniformity in the mixture, all parts not being uniformly saturated, or in other words, some sufficiently effective film surface was present which during the course of the operation, once being present, would tend to extend itself, due to capillary action, or circulation induced by changes in composition in the liquid phase.

I have stated in the preceding experiments, where yields were obtained, that these yields were "fully" 50%, etc. This phraseology is used advisedly since the yield was obtained by titration and in each case more or less of the cyanid was volatilized during

the course of the operation, especially owing to the extent of the surface present from which volatilization could take place. At different times Experiment 8 was repeated 5 with the exception that the period of operation was extended to one-half hour. In each case substantially no cyanid was found in the residue in the retort or tube, while further but little, if any, carbonate re- 10 mained, which in view of the preceding shorter term operations indicated that cyanid had been formed and had thereafter volatilized.

The following experiments are of interest 15 as showing the effectiveness of the process at relatively low temperatures:

Experiment 11.—This experiment was substantially like Experiment 8 with the exception that in the reaction mixture, one 20 half of the sodium carbonate was replaced by potassium carbonate. The temperature of the operation was 840° C. and the cyanid yield in the residue, upon titration, and at the expiration of a thirty minute run was 25 fully 45%. In this connection it may be of interest to note that the melting point of sodium carbonate is apparently about 860° C. while that of potassium carbonate is about 880° C. The eutectic point of the mixture 30 is about 690° C.

Experiment 12.—This experiment was a repetition of Experiment 11, except that the temperature of the operation was 780° C. and the time—forty minutes. The yield by 35 titration was 22%.

Experiment 13.—This experiment was a repetition of Experiment 12, save that the temperature was 730° C. and the time forty-five minutes. Yield by titration somewhat 40 over 2%. Obviously as the temperature was lowered the cyanid formation per given unit of time decreased. Correspondingly, other things being equal, more elevated temperatures afford markedly greater yields per 45 unit of time. Thus I have converted 45% of a given quantity of sodium carbonate into cyanid in two minutes, and over 80% in five minutes at 1060° C.

The efficiency of the catalyst in lowering 50 the temperature of cyanid formation and increasing the rate of its formation is even more strikingly shown by comparing the foregoing with the following statement of Dr. Ewan, in *Thorpe's Dictionary of Applied Chemistry*, Revised Edition, Vol. II, 55 1912, page 196:

"A few temperature measurements which the writer made with a platinum rhodium thermocouple showed that potassium vapor 60 is first evolved from a mixture of potassium carbonate and charcoal at about 1350° and that the formation of cyanid takes place very slowly at this temperature, the potassium cyanid volatilizing for the most part."

Experiments 4, 6 and 10 were made with

the very efficient reaction mixture above referred to, but their yields were unsatisfactory, at least when compared with the remaining experiments in the series. I may here observe, though, that the mixture used in these three experiments (4, 6 and 10) should give very satisfactory results when heated in twenty-five gram lots in a half inch gas pipe to 990° C. with the nitrogen.

Experiments 5, 7, 8 and 9 gave very rapid 75 conversion of carbonate into cyanid. Presumably in Experiments 5 and 7 the carbonate (sodium) melted and then penetrated by capillarity into the upper layer of tamping material, there to be rapidly and efficiently converted into cyanid. In Experiment 8 where the reacting mixture constituted the upper layer, the same result was attained by means of the capillary forces aided by gravity, while in Experiment 9 the 80 same result as in 8 was attained by thoroughly mixing the materials before they were tamped into the retort. Also when the very efficient reactive mixture was used in the thinner layer the yields varied from 85 almost nothing (4 and 6) to a comparatively poor yield in 10; presumably because the slight depth did not permit of sufficient drainage of the molten sodium carbonate from the upper layers of the mixture so as 90 to provide suitable reaction conditions. On the other hand when a larger quantity, such as twenty-five grams was tamped into a one-half inch iron pipe, presumably a portion of the molten carbonate in the upper portions 95 of the mixture drained to the lower portions so as to leave conditions in the upper part of the mass very favorable for cyanid formation thereby automatically producing conditions substantially similar to those provided intentionally in Experiments 5 and 7.

Use of apparatus shown by way of exemplification.—Assuming now, that the conditions prescribed have been observed in the disposition of material in the furnace shown 100 in the accompanying drawing, and that an adequate current of nitrogen is flowing through the tubes 2, each of the latter having in this case a mass 9 of intimately mixed 105 finely powdered iron, sodium carbonate and graphite in place therein. The actions and reactions take place as above described, sodium cyanid is formed in the interstices of the masses 9 and carbon monoxid gas flows off together with some excess nitrogen, through the tubes 5. It is to be understood, of course, that it is possible to operate quantitatively, so that substantially all of the 110 nitrogen, carbon and alkali metal compound are converted directly into cyanid; and all 115 of this can be done below the melting point of copper.

The cyanid which may be obtained from the residue of the masses 9 is substantially 120 100% pure; and as cyanid is exceedingly 125

soluble in water, lixiviation affords a convenient means for separating it from the residues of the reaction.

Air may be used in lieu of nitrogen and the arrangement of materials and parts shown in Fig. 4 has been found a convenient one in such cases.

Save for the provision of the oxygen consuming charcoal 7, and separating screens 10 8, the operation and apparatus is substantially the same as in the case just discussed. It may be well to note, however, that when using air it is advisable to operate at a slightly higher temperature, say 50° C., 15 than when using nitrogen. The charcoal combines with the oxygen content of the inflowing air so that a mixture of carbon monoxid and nitrogen, with possibly some carbon dioxid passes on to the reactive 20 mixture and the nitrogen reacts therewith, as before.

The heat necessary can be produced in the furnace tube or retort itself, thus almost entirely avoiding wear and tear on 25 the apparatus.

Time factor.—In the art of cyanid synthesis, we find frequent references to the yields obtained, but much less often to the time required for effecting the changes. I 30 wish to emphasize the very great importance of this time element and have aimed constantly in developing my process to make it an expeditious one.

When it is considered that the cost of 5 labor, wear and tear of apparatus, interest charges, loss of heat by radiation, conduction, and hot flue gases are, in general, direct functions of the time an operation requires; we realize that the time factor 40 may become, sometimes, of even greater importance than the ultimate or practicable yield. For example, the time given for certain processes is sometimes ten hours or more, with alleged yields of perhaps 50% 45 or much less, and under very drastic temperature conditions. My process affords far greater yields, and at very moderate temperatures, in from two to twenty-five minutes according to the conditions selected. In other words, my process will easily produce as much cyanid in several days as such processes can in a year. From this, it is evident that such an expeditious process is an enormously advantageous one even 55 if it were equally affected by the above items of expense, which, however, is not the case. It is also evident that in many cases it is desirable to sacrifice the yield somewhat providing a considerable saving in 60 time will result. Thus it may be found advantageous in certain cases to operate for a short time only upon a given mixture with the object of producing, let us say, a yield of 50%; thereafter removing the 65 cyanid formed in any suitable manner and

re-using the residue either alone or mixed with fresh material or materials, *e. g.* iron and sodium carbonate, as desired.

Résumé.—To epitomize, therefore the features of the process which, when observed, lead to consistent results and commercial 70 success in the production of cyanid:

(a) A material, *e. g.* iron, capable of readily dissolving carbon, must be employed as a catalytic agent.

(b) This material should be present in such quantity and should be in such condition as to afford an abundant solution or reactive surface.

(c) This surface should be maintained. 80 By this I do not mean that necessarily the same identical surface must be maintained, although even this is preferable, but that the extent of available surface considered as a whole should be substantially maintained 85 and that the carbon present therein should be maintained in sufficient quantity to permit of an energetic and practically continuous reaction taking place between said carbon and the nitrogen and free, or probably 90 free, alkali metal.

(d) The carbon should be present in such quantity and so disposed with respect to the carbon dissolving metal or agent that the reactive surface of the latter may be adequately and substantially continuously supplied. To this end also proper contact must be effected and maintained between the carbonaceous material and said metal, unless the latter be initially sufficiently carburized 100 to permit of continuous operation for a sufficiently extended period of time.

(e) The source of the alkali metal, or base of the compound sought, may either be intimately mixed with the catalytic material or otherwise. The essential feature to be observed is that the metallic vapor molecules must be developed or be supplied in adequate quantity and must either be in contact with or be able to make contact with the carbon supplying solution surface at the same instant as the nitrogen molecules.

(f) The reactive solution surface must not only be extensive and properly carburized but it must be accessible to the molecules of the gases or vapors participating in the reaction. In other words it must not be clogged up or covered with too thick films of liquid. When, therefore, the source of the base of the cyanogen compound 115 sought is a material which is molten at the temperature of the operation, *e. g.* sodium carbonate, and this liquid is present in excess, a sufficient extent of effective solution surface must still be preserved by affording 120 proper drainage facilities, or the equivalent thereof.

(g) The mass should be sufficiently porous to permit of the, at least, moderately free 130 passage of nitrogen therethrough whereby,

not only to supply nitrogen in adequate quantity to a sufficient extent thereof to favor the rapid production of cyanid; but, also, to sufficiently dilute and preferably to even dislodge or sweep away, the deleterious, inert carbon monoxid from the reaction surfaces.

(h) The temperature of the operation must be such as to afford the requisite molecular activity—I find in practice that it is advantageous to operate at from, let us say 780° C. up to somewhat less than the eutectic point of iron and carbon, when iron is the solvent used, and it is in solid form. The expeditious production of cyanid in fairly appreciable quantity, by this method, can be effected however at temperatures as low as, let us say, 730° to 780° C. The principal point to be observed in this connection is that at the lower temperatures the mixture must be more intimate and complete and the effective reactive surfaces more extensive than at higher temperatures. In other words, what we lose in temperature, must be made up in some other way. The lower temperatures of course, tend to prolong the life of the apparatus.

Referring again to the itemized characteristics and advantages of the process as a whole it will be seen that items 1 to 25 inclusive have been discussed or are self-evidently possible from the preceding disclosure.

There remains to be presented a more particular discussion of the use of the process in forming ammonia, and in the production of such by-products as hydrogen, formic acid, oxalic acid, etc.

Dr. Ewan states in his article in *Thorpe's Dictionary of Applied Chemistry*, above referred to, that—

“* * * * in every process now used for the production of cyanids, the nitrogen is derived from coal more or less directly.”

This is equivalent to saying that the cyanids are, in general, prepared from ammonia.

In contrast to this, one of the main objects of the present invention is the commercial production of ammonia through the instrumentality of cyanids produced from atmospheric nitrogen; thus making the production of ammonia independent of the use of initially combined nitrogen. Indeed I contemplate effecting, in some cases, the production of ammonia in such a manner that the cyanid formation will be but momentary or evanescent, so that in effect the ammonia may be produced not only synthetically but practically directly. This last will be hereinafter more fully referred to while considering the phase of the process which involves the formation of cyanid as a definite and intermediate step.

65 Ammonia.—Assuming that the apparatus

shown by way of exemplification has been charged with iron, carbon and a preferably inexpensive alkali compound, all in suitable form or condition and properly disposed with respect to each other to yield alkali metal cyanid in accordance with equation 4.

After the cyanid forming reaction has been effected to the desired extent, the residue consists chiefly of a mixture of iron, carbon and, for example, sodium cyanid, and this residue is especially well adapted for the production of ammonia, without the necessity of previously removing the cyanid content thereof. For example, the mass from the reaction may be cooled to a suitable temperature and a current of steam may then be passed over or through it. Ammonia will be produced according to the following equation.

The equations 4 and 9 show that we have here a cyclic process for producing ammonia from air and water through the instrumentality of carbon by alternately passing nitrogen or steam through a mixture consisting of iron, carbon and, for example, sodium carbonate.

If desired, the carbon monoxid and hydrogen may be burned with air, thus producing heat, which may be utilized in the process, and a mixture of carbon dioxid, nitrogen and water. The water condenses and the carbon dioxid and nitrogen together with the ammonia already formed may be passed into a solution of sodium chlorid, as in the ammonia-soda process. The carbon dioxid of the mixture is thus ultimately utilized to form sodium bicarbonate, or sodium carbonate, leaving the nitrogen in a fairly pure form for use in the preparation of another portion of cyanid according to equation 4.

The process is admirably adapted for use with the ammonia-soda process as it may utilize the waste atmospheric nitrogen from this process to furnish the pure ammonia required in the latter process, very cheaply.

The expense of the ammonia as well as the troubles arising from the impurities liable to be contained in commercial ammonia are at present serious obstacles to the economical operation of the ammonia-soda process; but both of these difficulties are obviated if my process is used in connection therewith.

The sodium carbonate acts cyclically to fix nitrogen by being transformed into cyanid (equation 4) and then the cyanid is changed back into carbonate, (equation 9), by the use of steam. If desired, we may start with the cyanid instead of the carbon.

ate, in this cycle. For example, a mixture of potassium cyanid, carbon and iron may be heated in a current of steam until a substantially quantitative yield of ammonia is obtained. The steam is then displaced by a current of nitrogen and the temperature is raised to about 1100° C. In a short time the action will be completed and the retort will be found to contain much cyanid; the 10 potassium carbonate having again been transformed into cyanid. Upon adding carbon as required, the process may be repeated over and over again as the cyanid or carbonate acts cyclically while the iron acts catalytically. The temperature should not 15 be too high, otherwise too much oxidation results from the steam and there is more tendency for cyanogen compounds to pass over with the ammonia.

20 When the temperature is adequate but not excessive, very little of the cyanogen compounds will pass over with the ammonia, and even these can be recovered very easily by using suitable scrubbers. If desired, the 25 ammonia may be obtained from the scrubbers in anhydrous form.

My invention also contemplates, as I have previously intimated, the production of ammonia in such manner that the cyanid formation will be transitory or evanescent. To 30 so effectuate the process it is merely necessary to reduce the temperature of the operation to a point (approximately 725° C.) where while the reaction involved in equation 35 4 is proceeding, the reaction shown in equation 9 may also occur. Under such conditions the catalytic material, iron, previously considered, is supplemented by the alkali metal carbonate which now may be 40 regarded as an auxiliary catalyst. The equation may be represented thus:

45 In this case one of the catalysts (e. g. iron) probably acts passively or merely as a solvent for one or more of the actively participating elements; while the second or auxiliary catalyst is itself actively involved in the reaction. The cyanid is probably intermediately produced, and in effect simultaneously with the ammonia. If desired, 50 however, the production of ammonia may be effected at the same or a slightly higher temperature, let us say for example, 750° C., by passing the nitrogen current until a proper cyanid formation has been effected, then 55 substituting steam for the nitrogen current, thereafter alternating the nitrogen and steam, thus also in effect using the alkali carbonate as a catalyst, the temperature being maintained substantially constant, if desired.

Nitrogen and its elimination from combustible gases.—The disclosures in the process show in a number of instances that atmospheric nitrogen is obtained as a waste product, and that this nitrogen may then 70 serve as a source of nitrogen for the synthesis of cyanids. Also, the disclosures show that some commercial combustible gases containing nitrogen may be used to supply the nitrogen for cyanid synthesis with a consequent purification, freeing the gas from 75 nitrogen. For example, a gas may contain, let us say, 30 to 40% of combustible material such as carbon monoxid, with the remainder made up substantially of nitrogen, 80 with consequent low calorific intensity. By removing the nitrogen from such a gas in the cyanid synthesis, the resulting gas would consist almost entirely of combustible material and it would be far more 85 valuable on account of its high calorific intensity.

General remarks.—Owing to the numerous possibilities of the process, I have only described some of the more important steps 90 involved, hence I wish to be limited only by the general spirit of the above disclosures and by the appended claims.

For convenience, I have described most of the experiments, and written the corresponding equations, for sodium compounds but these descriptions are intended to apply to alkali compounds generally, and, where applicable, to metals capable of performing like functions in the process.

100 In certain of the appended claims I have used the term "vapor" and in such cases where not otherwise specifically limited or restricted, this term is to be regarded as of sufficient breadth to cover, for example, both alkali metal vapor and the vapor of an alkali metal compound, e. g. sodium carbonate, etc.

105 Having thus described my invention, what I claim is:

110 1. The process of fixing atmospheric nitrogen which comprises effecting a vigorous reaction in which initially combined alkali metal, initially free nitrogen and dissolved carbon participate to form a cyanogen compound, by bringing the molecules of the 115 nitrogen into contact with the dissolved carbon present in an extended catalytic solution surface, while at the same time effecting a liberation of molecules of said alkali metal from the material with which they are combined, in the vicinity of said extended solution surface and maintaining a supply of nitrogen sufficient to immediately combine said carbon in said surface therewith and with substantially all of the alkali metal in 120 effect directly as liberated, whereby to substantially eliminate the tendency for the latter, by means of its vapor pressure, to establish a chemical equilibrium and retard the further liberation of said metal.

process becomes ineffective and maintaining a supply of nitrogen sufficient to combine with said carbon in said surface and with substantially all of the alkali metal in effect directly as liberated, whereby to substantially eliminate the tendency for the latter, by means of its vapor pressure, to establish a chemical equilibrium and retard the further liberation of said metal.

8. The process of fixing atmospheric nitrogen which comprises effecting a vigorous reaction in which initially combined alkali metal, initially free nitrogen and carbon dissolved in finely divided iron participate to form a cyanogen compound, by bringing the molecules of the nitrogen into contact with the dissolved carbon present in an extended surface of said iron while at the same time effecting a liberation of molecules of said alkali metal from the material with which they are combined, maintaining a supply of nitrogen sufficient to combine with said carbon in said surface and with the liberated alkali metal, and substantially continually replenishing the carbon in said surface, so as to maintain the carbon solution at substantially its maximum strength, by providing pulverulent masses of carbonaceous material in operative contact with said finely divided iron, throughout substantially the extent thereof.

9. The process of fixing atmospheric nitrogen which comprises effecting a vigorous reaction in which initially combined alkali metal, initially free nitrogen and dissolved carbon participate to form a cyanogen compound, by bringing the molecules of the nitrogen into contact with the dissolved carbon present in an extended catalytic solution surface, effecting a liberation of molecules of said alkali metal from the material with which they are combined, maintaining a supply of nitrogen sufficient to combine with said carbon in said surface and with substantially all of the molecules of said alkali metal encountering said surface and replenishing the carbon in said surface so as to maintain the carbon solution at substantially its maximum strength.

10. The process of fixing atmospheric nitrogen which comprises effecting a vigorous reaction at a temperature above 700° C. but below a temperature whereat the process becomes ineffective, in which the alkali metal base of a compound containing oxygen, initially free nitrogen and carbon dissolved in iron participate to form a cyanogen compound, by bringing the molecules of the nitrogen into contact with the dissolved carbon present in an extended surface of the iron, while at the same time effecting a liberation of the alkali metal from the material with which it is combined, the oxygen of said alkali metal compound being combined with carbon to

form an oxid of the latter element and maintaining an extended reactive surface throughout the mass of said iron by conducting the operation at a temperature below the eutectic point of the carbon-containing iron.

11. The process of fixing atmospheric nitrogen which comprises effecting a liberation of alkali metal vapor from a compound of the same, substantially preventing the liberated metal from exercising a reaction retarding vapor pressure upon the residue of said compound by intermingling a current of free nitrogen with the so liberated alkali metal and reacting upon the mixture with carbon held in solution in a mass of catalytic material, to form a cyanogen compound of said alkali metal.

12. The process of fixing atmospheric nitrogen which comprises bringing initially free nitrogen into contact with dissolved carbon present in an extended catalytic solution surface and there combining said dissolved carbon and said nitrogen with an element capable of acting as the base of a cyanogen compound, said element being initially present in chemical combination with at least one other element, to form a cyanogen compound of said first mentioned element, the while maintaining said solution surface effective by efficiently supplying fresh carbon thereto from a non-gaseous source of said carbon.

13. The process of fixing atmospheric nitrogen which comprises effecting a liberation of alkali metal vapor from a compound of the same, substantially preventing the liberated metal from exercising a reaction retarding vapor pressure upon the residue of said compound by intermingling a current of free nitrogen with the so liberated alkali metal and reacting upon the mixture with carbon held in solution in a mass of catalytic material disposed in the immediate vicinity of said alkali metal compound, to form a cyanogen compound of said alkali metal.

14. The process of fixing atmospheric nitrogen which comprises effecting a liberation of alkali metal from a compound of the same, substantially preventing the liberated metal from exercising a reaction retarding effort upon the residue of said compound, by intermingling free nitrogen with the so liberated alkali metal and reacting upon the mixture with carbon held in solution in a mass of catalytic material, to form a cyanogen compound of said alkali metal.

15. The process of fixing atmospheric nitrogen which comprises effecting a liberation of alkali metal from a compound of the same, substantially preventing the liberated metal from exercising a reaction retarding effort upon the residue of said compound by intermingling free nitrogen with the so

liberated alkali metal and reacting upon the mixture with carbon held in solution in a mass of iron, to form a cyanogen compound of said alkali metal.

16. The process of fixing atmospheric nitrogen which comprises effecting a liberation of alkali metal from a compound of the same, substantially preventing the liberated metal from exercising a reaction retarding effort upon the residue of said compound by intermingling free nitrogen with the so liberated alkali metal and reacting upon the mixture with carbon held in solution in a mass of finely divided catalytic material to form a cyanogen compound of said alkali metal.

17. The process of fixing atmospheric nitrogen which comprises effecting a liberation of alkali metal from a compound of the same, substantially preventing the liberated metal from exercising a reaction retarding action upon the residue of said compound by intermingling free nitrogen with the so liberated alkali metal and reacting upon the mixture with carbon held in solution in a mass of catalytic material presenting an enormously extended surface, to form a cyanogen compound of said alkali metal.

18. The process of fixing atmospheric nitrogen which comprises treating an alkali metal compound to obtain a vapor therefrom by subjecting said compound to heat and to capillary action, the latter whereby to form an extended film surface of the same at which said vapor is produced, and vigorously reacting upon said vapor simultaneously with free nitrogen and with carbon in solution in a mass of catalytic material, to form a cyanogen compound of said alkali metal.

19. The process of fixing atmospheric nitrogen which comprises treating an alkali compound to obtain a vapor therefrom by subjecting said compound to heat and to capillary action, the latter whereby to form an extended film surface of the same at which said vapor is produced, and vigorously reacting upon said vapor simultaneously with free nitrogen and with carbon in solution in a mass of catalytic material presenting an enormously extended surface, to form a cyanogen compound of said alkali metal.

20. The process of fixing atmospheric nitrogen which comprises treating an alkali compound to obtain a vapor therefrom by subjecting said compound to heat and to capillary action, the latter whereby to form extended film surface of the same at which said vapor is produced, and vigorously reacting upon said vapor simultaneously with free nitrogen and with carbon in solution in a mass of metal belonging to the iron group, to form a cyanogen compound of said alkali metal.

21. The process of fixing nitrogen which comprises bringing initially free nitrogen into contact with dissolved carbon present in an extended catalytic solution surface and there combining said dissolved carbon and said nitrogen with alkali metal, the latter being initially present in chemical combination with at least one other element, to form a cyanogen compound of said alkali metal, the while maintaining said solution surface effective by continuously and efficiently supplying fresh carbon thereto.

22. The process of fixing nitrogen which comprises bringing initially free nitrogen into contact with dissolved carbon present in an extended catalytic solution surface and there combining said dissolved carbon and said nitrogen with alkali metal, to form a cyanogen compound of said alkali metal, the while maintaining said solution surface effective by continuously and efficiently supplying fresh carbon thereto.

23. The process of fixing nitrogen which comprises effecting a vigorous reaction, from participation in which atmospheric oxygen is substantially completely excluded, by bringing initially free nitrogen into contact with dissolved carbon present in an extended catalytic solution surface and there combining said dissolved carbon and said nitrogen with alkali metal, the latter being initially present in chemical combination with at least one other element, to form a cyanogen compound of said alkali metal, the while maintaining said solution surface effective by continuously and efficiently supplying fresh carbon thereto.

24. The process of fixing nitrogen which comprises effecting a vigorous reaction, from participation in which atmospheric oxygen is substantially completely excluded, by bringing initially free nitrogen into contact with dissolved carbon present in an extended catalytic solution surface and there combining said dissolved carbon and said nitrogen with alkali metal, to form a cyanogen compound of said alkali metal, the while maintaining said solution surface effective by continuously and efficiently supplying fresh carbon thereto.

25. The process of fixing nitrogen which comprises bringing initially free nitrogen into contact with dissolved carbon present in an extended catalytic solution surface and there combining said dissolved carbon and said nitrogen with a metal capable of acting as the base of a cyanogen compound, said metal being initially present in chemical combination with at least one other element, to form a cyanogen compound of said metal, the while maintaining said solution surface effective by continuously and efficiently supplying fresh carbon thereto.

26. The process of fixing nitrogen which comprises bringing initially free nitrogen

- into contact with dissolved carbon present in an extended catalytic solution surface and there combining said dissolved carbon and said nitrogen with a metal capable of acting as the base of a cyanogen compound, to form a cyanogen compound of said metal, the while maintaining said solution surface effective by continuously and efficiently supplying fresh carbon thereto. 5
27. The process of fixing nitrogen which comprises bringing initially free nitrogen into contact with carbon dissolved in a finely divided catalytic material presenting an extended solution surface, and combining the dissolved carbon present in said surface with said nitrogen and with a metal initially present in chemical combination with at least one other element, to form a cyanogen compound of said metal, the while maintaining said solution surface effective by continuously supplying fresh carbon thereto, said surface being of such extent as to insure a reaction between said carbon, nitrogen and metal, of great vigor. 10
28. The process of fixing nitrogen which comprises bringing initially free nitrogen into contact with carbon dissolved in a finely divided catalytic material presenting an extended solution surface, and combining the dissolved carbon present in said surface with said nitrogen and with a metal capable of directly uniting with free nitrogen and carbon in solution to form a cyanogen compound the base of which is the said metal, to form said cyanogen compound, the while maintaining said solution surface effective by continuously supplying fresh carbon thereto, said surface being of such extent as to insure a reaction between said carbon, nitrogen and metal, of great vigor. 15
29. The process of fixing nitrogen which comprises bringing initially free nitrogen into contact with carbon dissolved in a finely divided catalytic material presenting an extended solution surface, combining the dissolved carbon present in said surface with said nitrogen and with a metal initially present in chemical combination with at least one other element, to form a cyanogen compound of said metal and maintaining said solution surface effective by supplying fresh carbon thereto, said surface being adhesive at the temperature of the operation and portions thereof being in intimate and effective contact with masses of carbon supplying material. 20
30. The process of fixing nitrogen which comprises bringing initially free nitrogen into contact with carbon dissolved in a finely divided catalytic material presenting an extended, rough, solution surface, and combining the dissolved carbon present in said surface with said nitrogen and with a metal initially present in chemical combination with at least one other element, to form a cyanogen compound of said metal and maintaining said solution surface effective by supplying fresh carbon thereto, said surface being of such extent as to insure a reaction between said carbon, nitrogen and metal, of great vigor. 25
31. The process of fixing nitrogen which comprises bringing initially free nitrogen into contact with carbon dissolved in finely divided catalytic material presenting an extended solution surface and disposed to form a porous mass into which the nitrogen can readily penetrate, combining the dissolved carbon present in said surface throughout a large portion of the interior of said mass, with said nitrogen and with an alkali metal initially present in a compound of the same other than a cyanogen compound, to form a cyanogen compound of said alkali metal and maintaining said solution surface effective by supplying fresh carbon thereto, said surface being of sufficient extent to insure a reaction between said carbon, nitrogen and alkali metal, of great vigor. 30
32. The process of fixing nitrogen which comprises bringing initially free nitrogen into contact with carbon dissolved in finely divided catalytic material presenting an extended solution surface and disposed to form a porous mass into which the nitrogen can readily penetrate, combining the dissolved carbon present in said surface throughout a large portion of the interior of said mass, with said nitrogen and with an alkali metal initially present in a compound of the same other than a cyanogen compound, to form a cyanogen compound of said alkali metal and maintaining said solution surface effective by supplying fresh carbon thereto, said surface being of sufficient extent to insure a reaction between said carbon, nitrogen and alkali metal of such vigor as to convert over fifty per cent. of said alkali metal compound to said cyanogen compound in less than one half hour. 35
33. The process of fixing nitrogen which comprises bringing initially free nitrogen into contact with carbon dissolved in finely divided iron presenting an extended solution surface and disposed to form a porous mass into which the nitrogen can readily penetrate, combining the dissolved carbon present in said surface, throughout a large portion of the interior of said mass, with said nitrogen and with an alkali metal initially present in a compound of the same other than a cyanogen compound, to form a cyanogen compound of said alkali metal and maintaining said solution surface effective by supplying fresh carbon thereto, said surface being of sufficient extent as to insure a reaction between said carbon, nitrogen and alkali metal, of great vigor. 40
34. The process of fixing nitrogen which

comprises bringing initially free nitrogen into contact with carbon dissolved in pulverulent catalytic material which can be passed through a sieve of substantially sixty mesh to the inch, and combining the dissolved carbon present in the surface of said material with said nitrogen and with a metal which is capable of being so combined and of acting as the base of a cyanogen compound which is stable at the temperature of the operation and maintaining said surface effective by supplying fresh carbon thereto.

35. The process of fixing nitrogen which comprises bringing initially free nitrogen into contact with carbon dissolved in pulverulent catalytic material which can be passed through a sieve of substantially sixty mesh to the inch, combining the dissolved carbon present in the surface of said material with said nitrogen and with a metal which is capable of being so combined and of acting as the base of a cyanogen compound which is stable at the temperature of the operation and recarburizing said surface by maintaining contact between portions thereof and pulverulent masses of carbonaceous material, the latter being less finely divided than said catalytic material.

30. 36. The process of fixing nitrogen which comprises bringing initially free nitrogen into contact with carbon dissolved in pulverulent catalytic material which can be passed through a sieve of substantially sixty mesh to the inch, combining the dissolved carbon present in the surface of said material with said nitrogen and with a metal which is capable of being so combined and of acting as the base of a cyanogen compound which is stable at the temperature of the operation and recarburizing said surface by maintaining contact between portions thereof and pulverulent masses of carbonaceous material.

45. 37. The process of fixing nitrogen which comprises bringing initially free nitrogen into contact with carbon dissolved in powdered iron which can be passed through a sieve of substantially sixty mesh to the inch, combining the dissolved carbon, present in the surface of said iron, with said nitrogen and with an alkali metal and maintaining said surface effective by supplying fresh carbon thereto.

55. 38. The process of fixing nitrogen which comprises bringing initially free nitrogen into contact with carbon dissolved in powdered iron which can be passed through a sieve of substantially sixty mesh to the inch, combining the dissolved carbon, present in the surface of said iron, with said nitrogen and with an alkali metal.

60. 39. The process of fixing nitrogen which comprises bringing initially free nitrogen into contact with carbon dissolved in pow-

dered iron which can be passed through a sieve of substantially sixty mesh to the inch, combining the dissolved carbon, present in the surface of said iron, with said nitrogen and with an alkali metal and maintaining 70 said surface effective by supplying fresh carbon thereto from carbonaceous masses capable of being passed through a sieve of substantially twenty mesh to the inch, said carbonaceous masses being intimately com- 75 mingled with the iron.

40. The process of fixing nitrogen which comprises bringing initially free nitrogen into contact with carbon dissolved in powdered iron which can be passed through a 80 sieve of substantially sixty mesh to the inch, combining the dissolved carbon, present in the surface of said iron, with said nitrogen and with an alkali metal and maintaining said surface effective by supplying fresh 85 carbon thereto from carbonaceous masses capable of being passed through a sieve of substantially twenty mesh to the inch.

41. The process of fixing nitrogen which comprises directly combining free nitrogen, 90 the carbon dissolved in a mass of solvent for the same which has, in the aggregate, a relatively enormous exposed surface in proportion to its bulk, and a metal capable of combining with nitrogen and carbon and of acting 95 as the base of a cyanogen compound under the conditions of the operation, to copiously form said compound, by liberating said metal from an extended reactive film of a molten compound of the same and 100 causing the molecules of liberated metal and said nitrogen to co-incidently contact with said surface.

42. The process of fixing nitrogen which comprises directly combining free nitrogen, 105 the carbon dissolved in a mass of solvent for the same which has, in the aggregate, a relatively enormous exposed surface in proportion to its bulk, and an alkali metal capable of combining with nitrogen and carbon and of acting 110 as the base of a cyanogen compound under the conditions of the operation, to copiously form said compound, by liberating said alkali metal from an extended reactive film of a molten compound of 115 the same and causing the molecules of liberated alkali metal and said nitrogen to co-incidently contact with said surface.

43. The process of fixing nitrogen which comprises directly combining free nitrogen, 120 the carbon dissolved in a mass of solvent for the same which has, in the aggregate, a relatively enormous exposed surface in proportion to its bulk, and a metal capable of combining with nitrogen and carbon and of acting 125 as the base of a stable cyanogen compound under the conditions of the operation, to copiously form said compound, by liberating said metal from an extended reactive film of a molten compound of the same, 130

which is superimposed upon a portion at least of said surface and causing the molecules of liberated metal and said nitrogen to co-incidently contact with said surface.

44. The process of fixing nitrogen which comprises combining free nitrogen, the carbon dissolved in a mass of solvent for the same which has, in the aggregate, a relatively enormous exposed surface in proportion to its bulk, and a metal capable of combining with nitrogen and carbon and of acting as the base of a stable cyanogen compound under the conditions of the operation, to copiously form said compound, by liberating said metal from an extended reactive film of a molten compound of the same which is superimposed upon a portion at least of said surface and causing the molecules of liberated metal and said nitrogen to co-incidently contact with said surface, said film being sufficiently thin over a large extent of said surface to allow of the nitrogen molecules penetrating the same.

45. The process of fixing nitrogen which comprises maintaining by capillarity an extensive thin film of a molten compound one of the constituent elements of which is a metal capable of combining with nitrogen and carbon and of acting as the base of a stable cyanogen compound under the conditions of the operation, flowing free nitrogen over said film whereby to facilitate the dissociation of the same and effecting a reaction in which said nitrogen, the metal so supplied by said film and carbon in solution participate, to form said compound.

46. The process of fixing nitrogen which comprises directly combining free nitrogen, the carbon dissolved in a mass of solvent for the same, which has, in the aggregate, a relatively enormous exposed surface in proportion to its bulk, and a metal capable of combining with nitrogen and carbon and of acting as the base of a stable cyanogen compound under the conditions of the operation, to copiously form said compound, by causing the molecules of said metal and said nitrogen to impinge against said surface simultaneously, said surface being substantially exposed and freely accessible to both said nitrogen and metal, whereby the two last mentioned elements may freely combine with said carbon.

47. The process of fixing nitrogen which comprises bringing initially free nitrogen into contact with an extended surface of molten material comprising, as one of the constituent elements thereof, a metal capable of combining with nitrogen and carbon and of acting as the base of a stable cyanogen compound under the temperature conditions of the operation, liberating said metal from said material and combining said metal and nitrogen with the carbon contained in an extended surface of catalytic

material having carbon dissolved therein, to form said cyanogen compound.

48. The process of fixing nitrogen which comprises bringing initially free nitrogen into contact with an extended surface of molten material comprising, as one of the constituent elements thereof, a metal capable of combining with nitrogen and carbon and of acting as the base of a stable cyanogen compound under the temperature conditions of the operation, liberating said metal from said material, combining said metal and nitrogen with the carbon contained in an extended surface of catalytic material having carbon dissolved therein, to form said cyanogen compound and maintaining a large extent of said surface substantially free from the bulk of said molten material, whereby to afford free access of the nitrogen and metal molecules thereto.

49. The process of fixing nitrogen which comprises maintaining by capillarity an extensive film of a molten compound one of the constituents of which is a metal capable of combining with nitrogen and carbon and of acting as the base of a stable cyanogen compound under the temperature conditions of the operation, flowing free nitrogen over said film whereby to facilitate the formation of a vapor from the same and effecting a vigorous reaction in which said nitrogen, the vapor so supplied by said film and the dissolved carbon present in an extended surface of a solvent for said carbon, participate to form said compound.

50. The process of fixing nitrogen which comprises maintaining by capillarity an extensive film of a molten compound one of the constituent elements of which is a metal capable of combining with carbon and nitrogen and of acting as the base of a stable cyanogen compound under the temperature conditions of the operation, flowing free nitrogen over said film whereby to facilitate the formation of a vapor from the same, effecting a vigorous reaction in which said nitrogen, the vapor so supplied by said film and the dissolved carbon present in an extended surface of a solvent for said carbon, participate to form said compound and maintaining said surface effective by supplying carbon thereto to replace that consumed in the reaction.

51. The process of fixing nitrogen which comprises maintaining by capillarity an extensive film of a molten compound one of the constituent elements of which is a metal capable of combining with carbon and nitrogen and of acting as the base of a stable cyanogen compound under the conditions of the operation, flowing free nitrogen over said film whereby to facilitate the formation of a vapor from the same and effecting a vigorous reaction in which said nitrogen, the vapor so supplied by said film and the

dissolved carbon present in an extended surface of a solvent for said carbon, participate to form said compound, a large portion of said film being directly in contact with a large portion of said surface.

52. The process of fixing nitrogen which comprises maintaining by capillarity an extensive film of a molten compound one of the constituent elements of which is a metal capable of combining with carbon and nitrogen and of acting as the base of a cyanogen compound under the temperature conditions of the operation, flowing free nitrogen over said film whereby to facilitate the formation of a vapor from the same and effecting a vigorous reaction in which said nitrogen, the vapor so supplied by said film and the dissolved carbon present in an extended surface of a solvent for said carbon, participate to form said compound, a large portion of said film being directly in contact with a large portion of said surface and when so in contact said film being main-

tained for a considerable extent thereof of such thinness as to permit of access to said surface by the gaseous participants in said reaction.

53. The process of fixing atmospheric nitrogen which comprises treating a compound, which contains an element capable of acting as the base of a cyanogen compound, to obtain a vapor therefrom by subjecting said compound to heat and to capillary action, the latter whereby to form an extended film surface of said first mentioned compound at which said vapor is produced, and vigorously reacting upon said vapor simultaneously with free nitrogen and with carbon in solution in a mass of catalytic material, to form said cyanogen compound.

In witness whereof, I subscribe my signature, in the presence of two witnesses.

JOHN E. BUCHER.

Witnesses:

NORMAN E. HOLT,

HOWARD C. RUPLEY.
